[57] **CLAIM**

The ornamental design for an electronically controlled clothing receptacle or similar article, as shown and described.

DESCRIPTION

FIG. 1 is a perspective view of an electronically controlled clothing receptacle or similar article showing my new design;

FIG. 2 is a front elevational view thereof;

FIG. 3 is a top plan view thereof;

FIG. 4 is a right side elevational view thereof; and

FIG. 5 is a left side elevational view thereof.

The undisclosed rear and bottom are substantially flat and unornamented.

FIG. 1

FIG. 2

FIG. 3

FIG. 4

FIG. 5
